(57) **CLAIM**

The ornamental design for a folding exercise climbing machine, as shown and described.

DESCRIPTION

FIG. 1 is a front perspective view of a folding exercise climbing machine showing my new design, in a first position, with the handles in a first position;

FIG. 2 is a front elevation view thereof, in the first position, with the handles in the first position;

FIG. 3 is a rear elevation view thereof, in the first position, with the handles in the first position;

FIG. 4 is a right side elevation view thereof, in the first position, with the handles in the first position;

FIG. 5 is a left side elevation view thereof, in the first position, with the handles in the first position;

FIG. 6 is a top view thereof, in the first position, with the handles in the first position;

FIG. 7 is a bottom view thereof, in the first position, with the handles in the first position;

FIG. 8 is a rear perspective view thereof, in the first position, with the handles in the first position;

FIG. 9 is a front perspective view thereof in a folded configuration, with the handles in a second position;

FIG. 10 is a front elevation view thereof in a folded configuration, with the handles in the second position;

FIG. 11 is a rear elevation view thereof in a folded configuration, with the handles in the second position;

FIG. 12 is a right side elevation view thereof in a folded configuration, with the handles in the second position;

FIG. 13 is a left side elevation view thereof in a folded configuration, with the handles in the second position;

FIG. 14 is a top view thereof in a folded configuration, with the handles in the second position;

FIG. 15 is a bottom view thereof in a folded configuration, with the handles in the second position;

FIG. 16 is a rear perspective view thereof in a folded configuration, with the handles in the second position;

FIG. 17 is an enlarged perspective view of the handlebars of the folding exercise climbing machine in the first position; and,

(Continued)

FIG. 18 is an enlarged perspective view of the handlebars in the second position.
